UNITED STATES PATENT OFFICE.

JOHN COFFIN, OF JOHNSTOWN, PENNSYLVANIA; ELIZABETH F. COFFIN (EXECUTRIX OF SAID JOHN COFFIN, DECEASED) ASSIGNOR TO THE CAMBRIA IRON COMPANY.

APPARATUS FOR COATING WIRE.

SPECIFICATION forming part of Letters Patent No. 451,220, dated April 28, 1891.

Application filed May 20, 1889. Serial No. 311,449. (No model.)

To all whom it may concern:

Be it known that I, JOHN COFFIN, a citizen of the United States, residing at Johnstown, in the county of Cambria and State of Pennsylvania, have invented certain new and useful Improvements in Apparatus for Coating Wire; and I do hereby declare the following to be a full, clear, and exact description of the invention, such as will enable others skilled in the art to which it appertains to make and use the same.

In the art of coating wire with metal, commonly called "galvanizing," the wire passes through several tanks and baths, and to properly direct it through these tanks guides have to be arranged which deflect the wire at several points. These deflecting-guides cause considerable tension on the wire, and the total resistance is not the sum of the several resistances due to drawing over deflecting-guides, but is their product. Therefore where many baths are used and there are consequently many deflecting points the force required to draw the wire through this system is so great as to cause serious trouble.

My invention relates to means for overcoming the difficulties which have arisen from the severe tension of the wire; and the object of my invention is to cause the wire to be drawn through the tanks easily and prevent the several resistances due to changing the direction of the wire over the guides from being multiplied by each other. I accomplish this object by interposing between the acid bath and the metal bath a pair of driven rolls, around which the wire passes. These rolls are driven with a peripheral velocity greater than that of the wire in passage, and thereby aid the passage of the wire.

To make my invention more clear, I will now refer to the annexed two sheets of drawings, which form part of this specification, and in which—

Figure 1 represents a side elevation of my invention; Fig. 2, a front elevation of the same in part; Fig. 3, a plan of my invention, and Fig. 4 a diagram showing the manner of location and operation.

Like letters of reference refer to like parts throughout.

A represents a foundation-plate. B B are stands bolted on the foundation-plates. These stands support in suitable bearings (indicated by b) the shafts of two driven rolls. These rolls are represented by C C'. The shaft of 55 the rolls C is prolonged to receive on one end the pinion D outside of the bearing b. The shaft of the roll C' is prolonged at one end to receive the pinion D', which engages with the pinion D, and it is farther prolonged to receive the driving-pulley E and still farther prolonged to have the bearing f in the bracket F, the bracket F being bolted to the foundation-plate A.

Referring to Fig. 1, the position of the two 65 rolls is clearly shown, the arrows indicating their direction of revolution. W represents the wire in transit, the arrows indicating the direction of motion.

Referring to Fig. 4, G represents an acid-70 tank, and g a sandstone guide for the wire, commonly called a "sinker."

H represents the driving mechanism which has just been described.

K represents a preheating-furnace, which 75 is sometimes used to heat the wire prior to its entrance into the coating-metal.

L represents a bath of coating-metal, and l the sinker or guide for the wire in this bath.

R represents a reel for receiving the wire 80 driven in the direction of the arrow.

I do not limit myself to the exclusive use of such a reel for receiving the wire, as it may be led from the bath L to another machine or device, if necessary; or it may be led in a 85 straight or broken line by power or otherwise, or in other suitable manner, whereby the wire is caused to travel through the various devices at a speed less than the surface speed of the driving-rolls.

The manner of operating my invention is as follows: Referring to Fig. 4, W represents a wire in position through the acid bath, the driving-rollers, the preheating-furnace, and the coating-bath. The wire travels in the direction of the arrows, and the driving-rollers revolve in the direction of the arrows, the velocity of the wire being exceeded by the peripheral velocity of the rolls. We will suppose a force to be acting on the wire at w in 90 95 100

the direction of the arrow. After overcoming the resistances of the bends through the coating-bath L some tension will be caused at the point w' . This tension tightens the wire on the surface of the rolls, and this surface being driven faster than the wire is moving causes friction, which assists in moving the wire along and in drawing it through the acid bath G. To illustrate: No matter what the resistances at the various points may be, with a fixed amount of angular contact with the driving-rolls and a constant coefficient of friction the tension on the wire at the point at w^2 will be a constant ratio to the tension at w' .
15 Suppose this ratio be four to one. Then if it requires a force of four pounds applied at w^2 to move the wire in the direction of the arrow, a force of one pound applied at w' will tighten the wire enough on the rolls to cause the friction of the rolls, together with the pound force applied at w' , to exert a force on the wire equal to four pounds at the point indicated by w^2 . A single roll may be used by giving the wire one or more turns around this roll.
20 I do not favor this construction, because the wire is apt to become tangled by the ingoing
25

coil riding upon the others. However, I wish my invention to embrace this modification, and when I speak of a "pair of rolls" I consider a single roll with one or more coils of wire 30 around it to be an evident mechanical equivalent. .

Having fully described my improvement and the manner of operating the same, what I claim as my invention, and desire to secure 35 by Letters Patent, is—

In an apparatus for coating wire with metal, the combination of a tank for acid, a tank for molten metal, means for conveying the wire at a predetermined velocity through the tanks, 40 a roll arranged between the tanks and constructed to bear on the wire, and means for imparting to this roll a surface velocity greater than that of the wire in contact therewith, as set forth.

In testimony whereof I affix my signature in presence of two witnesses.

JOHN COFFIN.
